UNITED STATES PATENT OFFICE.

ALFRED MILROY NOLF, OF SALT LAKE CITY, UTAH.

MAGAZINE-FIREARM.

No. 807,044.

Specification of Letters Patent.

Patented Dec. 12, 1905.

Application filed June 30, 1903. Serial No. 163,763.

To all whom it may concern:

Be it known that I, ALFRED MILROY NOLF, a citizen of the United States, residing at Salt Lake City, in the county of Salt Lake and 5 State of Utah, have invented a new and useful Magazine-Firearm, of which the following is a specification.

This invention relates to magazine-firearms, and more especially to magazine-firearms of 10 what is generally known as the "box" type, in which the magazine consists of a box located adjacent to the breech of the firearm.

One of the principal objects of the invention is to provide a magazine-firearm of such construction that the two movements by which 15 the breech is opened and closed, the empty shell ejected, and a fresh cartridge introduced in its stead may comprise, first, a forward movement of the fore end of the firearm and, 20 second, a rearward movement, thus leaving the hand of the user at the end of the operation in suitable position for firing.

A further object of the invention is to provide a magazine-firearm having a sliding barrel 25 with improved mechanism for locking the barrel to the stock when the breech is closed.

A further object of the invention is to provide a magazine-firearm in which the length of the barrel obtainable in a firearm of given 30 length may be greater than in any of the types of magazine-firearms hitherto used without increasing the over-all length of the barrel and stock, thereby insuring better balance of the firearm and enabling the sights to be placed 35 nearer to the eye of the user.

A further object of the invention is to improve the construction of magazine-firearms, so that when the firearm is in position to be discharged the breech end of the barrel will 40 be covered by a solid casing, which will completely prevent the escape of gases from the breech of the firearm, and thus prevent danger of injury from that cause to the eyes of the user.

Another object of primary importance had 45 in view in the construction of my invention is to provide a double magazine consisting of two sections arranged on opposite sides of the firearm below the barrel and mechanism for removing the cartridges alternately from the 50 sections of the magazine to replace the cartridges discharged, thus increasing the capacity of the magazine of the firearm without adding materially to its size or marring its symmetry.

55 Other objects contemplated in the construc-

tion of my invention are to so construct a magazine-firearm that it may be loaded with greater facility than usual in such weapons, so that it may be carried with less inconvenience upon the shoulder or upon the saddle of 60 a horseman, so that the firearm may be readily "taken down" for convenience for carrying in a case and so that the parts of the mechanism of the firearm may be readily accessible for cleaning purposes whenever necessary. 65

In describing the construction and operation of the invention reference will be had to the accompanying drawings, forming a part of this specification, in which corresponding parts are designated by the same characters of 70 reference throughout the various views, it being understood that changes may be made in the form, proportions, and exact mode of assembling of the elements exhibited without departing from the spirit of the invention or 75 sacrificing any of its advantages.

In the drawings, Figure 1 is a view in side elevation of a sporting-rifle constructed in accordance with this invention. Fig. 2 is a side view of the breech end of the rifle-barrel and 80 the adjoining portion of the stock with parts broken away to show the lock mechanism and a portion of the mechanism associated with the magazine. Fig. 3 is a detail view, in longitudinal section, through the breech-block 85 and breech end of the barrel. Fig. 4 is a view of the breech-block looking from the front. Fig. 5 is a detail view of the hammer, trigger, and associated lock mechanism, showing the manner of cocking the hammer and setting the trigger. Fig. 6 is a detail view of a 90 portion of the lock mechanism, showing the construction of the sear, safety-set, and knock-off. Fig. 7 is a detail view showing principally the construction of the trigger and its 95 safety device. Fig. 8 is a top view of the hammer and indicator. Fig. 9 is a detail view of the trigger-set and spring associated therewith. Fig. 10 is a detail side view of the magazine - cover latch, parts being broken 100 away to show the mode of attachment of the spring. Fig. 11 is a top plan view of the magazine-cover latch with the spring broken away to show the construction of the latch. Fig. 12 is a view from the left side of the forward portion of the mechanism under the barrel for operating the barrel-lock and cartridge-shifting devices, the parts being in the 105 position taken when the breech of the rifle is closed. Fig. 13 is a similar view with the 110

breech of the rifle open and a cartridge raised by the elevator. Fig. 14 is a detail view showing the means for forcing a cartridge into the grasp of the elevator-jaws. Fig. 15 is a top plan view of the guide-bar. Fig. 16 is a detail view from the rear of the cartridge-elevator. Fig. 17 is a detail view from the front of the elevator. Fig. 18 is a detail view from above of the elevator. Fig. 19 is a detail view in perspective of one of the elevator-jaws. Fig. 20 is a detail view in perspective of the elevator with one of the jaws removed. Fig. 21 is a detail view, in vertical section, longitudinally of the rifle through the barrel-locking bolt, showing the means of raising and lowering the same. Fig. 22 is a front view of the barrel-locking bolt with the connecting-rod in engagement with the cam-lugs on the bolt. Fig. 23 is an inverted plan view of the under side of the barrel-strap and breech-piece, showing the switch-cam pivoted on the under surface of the barrel-strap. Fig. 24 is a detail view in plan, illustrating the operation of the switch-cam in shifting the cartridge-forks, the cam being shown in dotted lines over the rear portion of the forks in the position occupied by the cam at the beginning of a forward movement of the gun-barrel when the cartridge-forks are in the position shown in solid lines, the cam being shown in solid lines as it is just before the end of the forward movement is reached and in dotted lines again in the position taken at the end of the forward movement after the cam has been shifted by engagement with a lug on one of the spring-fingers which act as latches for the cartridge-forks. Fig. 25 is a view in vertical transverse section through the magazine-chambers and the barrel of the rifle. Fig. 26 is a view in vertical transverse section just in front of the guide-loop. Fig. 27 is a detail view from above of the latch in the fore end. Fig. 28 is a view, partly in elevation and partly in section, showing the modified form of the fore end and the guide-bar used in the military form of the rifle. Fig. 29 is a transverse section through the barrel and fore end of the military pattern. Fig. 30 is a detail view showing the modifications in the lock as used in the military pattern of rifle. Fig. 31 is a perspective view of a cartridge-clip for use with either pattern of the rifle.

In the figures of the drawings there is illustrated and in the following specification there will be described an embodiment of the invention in a rifle, as that is the form of the invention which will be most generally used; but it is to be understood that the same principles of operation may be applied with but slight modifications of the mechanism to a shotgun.

Referring to the drawings by reference characters, A designates the stock of the form of the rifle designed for sporting purposes.

65 B designates the frame containing the lock,

hammer, magazines, and the mechanism for shifting the cartridges from the magazine into alignment with the bore of the barrel.

C designates a combined trigger-guard and plate for closing the bottom of the frame B. 70

D designates the barrel of the rifle, E the fore end, and F a plate for closing the bottom of the magazine.

In the detailed description of the parts of the invention and their workings the mechanism will be considered in sections, and the construction and operation of the elements of each section will be disclosed as completely as possible separately from the other sections. 75

Following the plan above outlined the structure of the breech-block, firing, and cartridge-ejecting mechanisms will first be described. 80

1 designates the breech-block, which is of substantially cylindrical form and provided at its forward end with a head 1^a of larger diameter than the remainder of the breech-block and having at its rear end a solid extension 1^b. The breech-block is secured in position in a tubular container B' in the upper portion of the frame B and held in position by means of 85 a securing-screw 1^c, which engages a suitable socket in the solid extension 1^b. The under surface of the breech-block is cut away at 1^d to permit the passage of a hammer or striker hereinafter to be described. The firing-pin 2 95 consists of a reduced forward portion 2^a and an enlarged rear portion 2^b and is slidably mounted in the bore of the breech-block at its forward end and projects through a small opening in the head 1^a of the breech-block when 100 driven forward by the hammer or striker.

Mounted in a groove on the upper surface of the breech-block is an extractor 3, provided at its forward end with a catch-lug 3^a and at its rear end with a securing-lug 3^b. The latter engages a suitable opening in the breech-block and holds the extractor in proper relation thereto, with the catch-lug disposed a short distance in front of the head 1^a of the breech-block. The extractor is made of resilient material and is held normally in contact with the bottom of the groove on the upper surface of the breech-block in which it lies, but is susceptible of slight movement away from the bottom of said groove, especially at 110 its forward end, a certain amount of play being allowed by the opening 1^e in the head of the breech-block, through which the extractor 3 projects. This play of the extractor is provided in order to insure the engagement of the catch-lug 3^a with the rim of the cartridge when in the barrel of the rifle when it is desired to withdraw the shell therefrom. 115

At the lower side of the head 1^a of the breech-block and diametrically opposite to the extractor 3 there is provided a forwardly-projecting lug 1^f, having a rounded front end to cause it to pass readily under a cartridge. Immediately above the lug 1^f and slidably in a guide-channel provided therefor in the lower 120

- part of the breech-block is an ejector-pin 4, consisting of a reduced forward portion 4^a and an enlarged rear portion 4^b. The portion 4^a of the ejector passes through the opening in the end of the breech-block provided therefor, and the enlarged portion 4^b is held normally in contact with the rear surface of the head of the breech-block by means of an ejector-spring 6, which abuts at one end 5 against part 4^b of the ejector and at the other end against the end of a screw-plug 5. The screw-plug 5 serves not only to keep the ejector in its normal forward position by pressing against the rear end of the spring 6, but also retains the firing-pin 2 in the bore provided for it in the breech-block 1 by the engagement of the head of the screw 5 with a shoulder formed on the under surface of the firing-pin 2.
- 20 The firing-pin 2 is freely slideable in the opening provided for it in the breech-block, and when the rifle is in firing position the firing-pin is forced back to its rearward position by the cartridge in the barrel of the rifle. When 25 the hammer or striker hereinafter to be described strikes the rear portion of the firing-pin, it is driven forward in the usual manner against the cap in the cartridge and causes its discharge.
- 30 When the parts of the rifle are in firing position and a cartridge is in the barrel, the extractor 3 engages with the rim of the cartridge upon the upper side thereof, as shown in Fig. 3, and the ejector-pin is forced back against the pressure of spring 6 by contact with the lower portion of the head of the cartridge-shell. The extractor and the lug 1^f at this 35 time are both projecting into recesses provided for them in the end of the barrel and the head of the cartridge-shell rests against the head 1^a of the breech-block. After the rifle is fired the barrel is moved forward and the empty shell is drawn out by the action of the catch-lug 3^a on the forward end of the extractor. As soon as the shell is entirely free 45 of the barrel it is thrown upward and to the left by the force of spring 6 acting upon the ejector-pin 4, which presses against the lower portion of the head of the empty shell. The 50 movement of the shell to the left, as well as upward, is brought about by the arrangement of the extractor and ejector in a diametrical line across the head of the breech-block in oblique position, as shown.
- 55 The lock mechanism of the rifle is mounted on top of the combined trigger-plate and guard C, on the upper surface of which is secured a vertical plate 7, which coöperates with a "bridle" 16 to support most of the lock mechanism.
- 60 The hammer or striker 8 is of irregular form and is mounted to swing on a pivot-pin 8^a, screw-threaded at one end and engaging with a threaded opening in the upper forward corner of the plate 7. The striker 8 has a top
- of segmental form and is provided with a striking-surface 8^b, a shoulder 8^c for the engagement of a sear, with a rearward and downward projection 8^d, and with a cam-surface 8^e below the sear-engaging shoulder. The hammer has a portion of the metal of which it is formed cut away on the right face thereof adjacent to the pivot-pin 8^a to afford play for an eccentric lever 18, which is mounted to swing upon pivot-pin 8^a and which has a lug 18^a, 70 which engages with the hammer for the purpose hereinafter to be explained, and an arm 18^b of peculiar form, which is adapted to engage with the connecting-rod 30, as will be afterward explained. The trigger 9 is pivotally mounted on pivot-pin 9^a, which extends through plate 7 and a rib C' provided on the upper surface of the trigger-plate C. The trigger has a finger-pull 9^b, which projects downward through a slot in the plate C in the 80 usual manner. Above the pivot-pin 9^a the trigger has an upwardly and rearwardly extending arm 9^c, from which projects at the end thereof a pin 9^d for engagement with a slot in the operating-arm of the sear 21. The 90 body of the trigger 9 has a recess 9^e formed in the upper surface thereof to provide a seat for a pivoted safety-set 10, which is provided with a spring 10^a, which projects rearwardly and upwardly therefrom. In the front surface of the body of the trigger 9 is a recess 9^f for the entrance of a trigger-lock 11. The safety-set 10 swings through a considerable arc, its movement being limited by the forward wall of the recess 9^e, in which it is mounted, and a 100 set-screw 10^b, which extends upward and rearward through the body of the trigger 9 and engages a shoulder formed on the lower and rear surface of the safety 10.
- 105 The safety-lock 11 is slidably mounted upon the trigger-plate C, its movement thereon being limited by a pin 11^a, which projects through the safety-lock and through slots provided therefor in rib C' and the plate 7. The safety-lock 11 consists of a horizontally-disposed 110 body portion and a downward projection 11^b, which extends through a slot in plate C and forms means for operating the lock by hand. The horizontal portion of safety-lock is provided at the rear thereof on the left side with a 115 lug 11^c, which projects above the rest of the safety-lock and is adapted to engage with a downwardly-disposed lug on a pivoted latch 13. Just at the front of the lug 11^c the lock 11 has a recess 11^d, with which engages the 120 end of a lever 20, by means of which the safety-lock is automatically actuated, as will hereinafter appear.
- 125 12 designates the mainspring, which is supported upon a stud 12^a, projecting from the plate 7, upon which the mainspring is held by a projecting lug 7^a at the rear of plate 7 and a stud 12^b near the upper forward corner of the plate 7. Latch 13, mentioned above, is mounted to swing upon a screw 13^a, located 130

just beneath the stud 12^a, and said latch 13 comprises a rearwardly-extending arm 13^a, with a laterally-projecting terminal lug 13^b and a forwardly-projecting arm 13^c, having at the top a laterally-projecting lug 13^d and at the bottom a downwardly-projecting lug 13^e, which engages with the lug 11^c on the trigger-lock, as above specified.

A sear 21 is mounted to swing upon a stud 21^a, projecting from the plate 7 above the mainspring 12. The sear 21 comprises an upper portion 21^b, having a shoulder 21^c for engagement with the hammer or striker, and an arm 21^d, which projects downward from the stud 21^a and is provided near its lower end with a slot 21^e, adapted to be engaged by the pin 9^a on trigger-arm 9^c.

The irregular member 17, mounted to swing beneath the hammer 8, will be referred to as the "knock-off." The knock-off consists, preferably, of a pivot-pin 17^a, formed integral with the rest of the knock-off, an upwardly-projecting portion 17^b, and a lower curved portion 17^c, terminating at its rear end in a small hook 17^d for engagement with a lug upon the safety-set 10, as will hereinafter be explained.

All of the members of the lock mechanism hereinbefore described are held in proper relation by means of the bridle 16. The bridle 16 supports one end of stud 21^a and pivot-pin 17^a and is held in position by means of screws 8^a, 16^a, and 16^b. The screw 8^a, which forms the pivot-pin that supports the hammer 8, also supports the pivoted indicator-spring 19, which carries at its rearward end a screw 19^a, one end of which is engaged by the cam-surface 8^c on the hammer as it is forced backward in cocking, and the other end of which projects through an opening in the frame B to indicate the position of the hammer. A lug 19^b is formed on the indicator-spring adjacent to screw 19^a to engage the upper surface of bridle 16 and hold the indicator-spring in proper relation to the opening in frame B to permit the introduction of the screw 19^a through said opening into the indicator-spring. The combined guard and trigger-plate C is attached to the frame B by means of a screw C³ at the rear end thereof and a cross-pin 22.

At the forward end of the combined trigger plate and guard C is provided a locking-bolt 14 for the magazine-cover plate F. Locking-bolt 14 is slidably mounted in guideways formed in the plate C and is normally held in position by means of a spring 15, attached at one end to the plate C by a screw 15^a and engaging at the other end with an opening in the bolt 14. The frame B has the upper edges of the sides thereof forward of the lock mechanism bent inward to form guides for the backward-and-forward movement of the barrel D. The barrel D is provided at its rear end 65 with a breech-piece 23 and is secured rigidly

upon a grooved strap 24, which extends longitudinally of the barrel, and is provided along its edges, at the rear portion thereof, with grooves for engagement with the upper edges of the sides of the frame B, to which reference has already been made.

In the frame B under the barrel there is firmly secured, by means of screws, a guide-bar, (designated generally as 28,) which is of the peculiar contour illustrated in Fig. 15. The guide-bar 28 is secured to the frame B by screws 28^a, 28^b, and 28^c, the first of which passes through an eye formed at the extreme rear of the guide-bar 28 and engages with a dependent partition in the casing between the lock mechanism and the mechanism concerned more particularly in the operation of the magazine. The screws 28^b and 28^c pass through the bar 28 and engage with lugs provided on the walls of the frame B near the forward end thereof, as shown, thus affording a firm support for the guide-bar, upon which most of the strain attendant upon the operation of the magazine falls.

Slidably mounted upon the forward portion of the grooved barrel-strap 24 is a guide-loop 29, which has grooves cut in the sides thereof for the engagement of the sides of guide-bar 28. The loop 29 is slidably mounted upon the strap 24, but has its movement thereon limited by a stop-screw 24^b and by a pawl 25, pivoted in the loop 29 and actuated by a spring 25^a. The pawl 25 has at one end an upturned lug 25^b, adapted to engage a short slot 24^a in the barrel-strap 24. At the other end the pawl 25 terminates in a downwardly and forwardly disposed arm adapted to contact with a lug 28^d on the upper surface of guide-bar 28 for the purpose that will afterward appear.

To the lower portion of the guide-loop 29 is rigidly secured a frame 29^a, having two downwardly-facing openings 29^b, through which project the ends of a curved member 36, which is pivotally mounted in the frame 29^a and has at the rear a catch to engage with a catch-lug 28^h on bar 28. One end of member 36 is always projected through one of the openings 29^b by means of a spring 35, having a central longitudinal slot 35^a, through which the curved member 36 projects. Upon either side of the slot 35^a, just above the pivot-pin upon which the member 36 swings, is provided a small V-shaped elevation 35^b, and member 36 is provided on either side with a laterally-projecting lug 36^a, which is adapted to pass over said elevation and to cause the curved member 36 to remain at all times with one end or the other projecting downward through its opening 29^b. At the forward end of frame 29^a there is provided a transverse pin 29^c, which engages with recesses provided therefor in the sections of the fore end E. Upon the under surface of guide-bar 28, toward the rear thereof, are two downwardly-projecting longitudinal ribs 28^e, formed in

tegral therewith and spaced apart to provide a guideway for connecting-rod 30, to be described in detail later on. At the rear the ribs 28^e terminate in hooks 28^f for the engagement 5 of lugs 26^a at the rear of the cartridge-guide frame 26, which comprises the box-like portion 26^b, formed of sheet metal and provided at its forward end with outwardly-curved wings 36^c and the central rib 26^d, to which the box-like portion 26^b is attached and upon which at the rear end are formed the lugs 26^a, already mentioned. The rib 26^d forms the lower surface of a guideway for connecting-rod 30, above mentioned, and is attached 10 near its forward end to a pivot-screw 27^a, which extends through the ribs 28^e near their forward ends and forms the support of the cartridge-elevator lever 27.

The elevator-lever 27 is pivotally connected 20 at its rear end with the elevator-frame 41, provided at the back with guide-loops 41^a, through which project pins 28^g at the top of an upward projection 28^h near the rear of the guide-bar 28. The elevator-frame 41 carries two spring-jaws 42, mounted one on each side of the frame and adapted normally to lie in contact therewith, but capable of being forced away from the frame by the entrance of the head of a cartridge between them. The jaws 42 are 25 preferably curved on the inner faces, so as to obtain sufficient grasp of a cartridge to prevent its being thrown too high if the elevator-frame is operated very suddenly, and each of said jaws 42 is provided just in front of the back plate of the elevator-frame with a vertical groove for engagement with the flange upon the head of a cartridge. The connecting-rod 30, mentioned above as sliding between the ribs 28^e, is provided upon one side with a 30 stepped cam-groove 30^a for engagement with a stud 27^b at the forward end of the elevator-lever 27, and by the reciprocations of the connecting-rod 30 the elevator-lever is actuated in suitable relation to the operation of the 35 other mechanism of the rifle.

Connecting-rod 30 contacts at the forward limit of its movement with the catch-lug 28^j upon the under surface of the guide-bar 28 at the forward end thereof, and the rearward movement of the connecting-rod 30 is limited 50 by the contact of the stud 27^b with the end of cam-slot 30^a. The connecting-rod 30 is reciprocated by the movements of the sliding loop 29, to which the rod 30 is connected by the engagement of a downwardly-disposed stud 30^b upon the forward end of the rod with an opening in the rear of spring 35. Near the rear end of connecting-rod 30 there is provided on either side thereof a downwardly 55 and rearwardly extending groove 30^c for engagement with lugs upon a locking-bolt 34, presently to be described. To the rear of the groove 30^c the connecting-rod 30 is reduced in size and is provided upon the right with a 60 stud 30^d for engagement with the dependent

arm on eccentric-lever 18 of the lock, and upon the left is provided at the end thereof a small cam 30^e, which engages with a stud 20^a on the lever 20 to throw the safety-catch 11 to operative engagement with the recess provided 70 therefor in the trigger 9.

The locking-bolt 34 is slidably mounted in vertical grooves provided therefor in the side walls of the frame B and is held from movement therein under the influence of gravity 75 by means of a small spring 34^a, lying in a shallow groove upon one side of the locking-bolt and pressing against the side of the frame.

Locking-bolt 34 is provided with a large central opening for the passage of the rear 80 portion of guide-bar 28 without interference with the vertical movement of the locking-bolt and upon its upper surface is provided with a plurality of ribs 34^b, arranged transversely of the main portion of the locking-bolt and extending upwardly and forwardly 85 upon the lateral ears 34^c at either side thereof. The ribs upon the upper surface of the locking-bolt are adapted to engage with correspondingly-placed ribs upon the breech-piece 23, and owing to the inclination of the ribs on the lateral ears of the locking-bolt and upon the sides of the breech-piece the breech-block will be forced backward by a 90 sort of wedge action when the ribs of the locking-bolt come into engagement with the ribs on the breech-piece. When the gun is unbolted, the inclination of the ribs on the lateral ears of locking-bolt and on the breech-piece gives strong but slow forward impulse 95 to the barrel and completely extracts the shell. The transverse ribs on the body portion of the breech-piece and the corresponding ribs upon the top of the locking-bolt come into engagement when the locking-bolt is 100 forced completely home and coöperate to lock the barrel into very firm contact with the frame B.

Near the lower end thereof the locking-bolt 34 is provided with an opening for the 110 passage of the connecting-rod 30, and immediately above said opening there are placed a pair of inwardly-projecting inclined cam-lugs 34^d, which engage with a pair of grooves, already mentioned, upon the sides of the connecting-rod 30, by means of which the locking-bolt 34 is caused to move up and down 115 in the guides provided therefor in the casting B.

Upon the guide-bar 28, near the forward 120 end thereof, there is provided on the upper surface an opening for a screw 31^a, passing through a collar 31^b, to which are attached two rearwardly-extending forks 31, each of which is slightly resilient. The cartridge-forks extend backward within the frame B, within which they terminate, above the magazine-chambers, hereinafter to be described. Each cartridge-fork is provided on the under 125 side with a lug which engages an undercut 130

curved rib on the guide-bar 28. At the outer side of each of the forks there is secured a spring 32, which aids in the operation of the fork to shift the cartridges from the magazine-chambers into position to be engaged by the spring-jaws on the cartridge-elevator. On the under surface of the guide-bar 28, at the forward end thereof, are attached by screws 33^a two spring-fingers 33, each of which extends rearwardly and has projecting upward through openings provided therefor in the guide-bar two lugs 33^b and 33^c, respectively. Spring-fingers 33 serve as locks for the forks 31 in the manner to be hereinafter explained.

The magazine consists of two chambers B² and B³, formed within the frame B upon either side of the rear portion of the guide-bar 28, the outer walls of the chambers being formed by the side walls of the frame B and the inner walls by the cartridge-guide frame 26, already described. At the top of the chambers B² and B³ are provided curved inwardly-projecting wings B⁴ and B⁵, which prevent the upward movement of the cartridges beyond the desired level, and vertical ribs B⁶ and B⁷ are provided on the inner surfaces of said walls of the frame B to hold the cartridges out of contact therewith and permit the passage of springs 32, upon the cartridge-forks, between the cartridges 30 and the side walls of the frame B.

The cartridges are introduced into the chambers B² and B³ from the under side, the rifle being reversed in position to permit the introduction of the cartridges, and the magazine is closed by the cover-plate F, which is pivotally supported at the forward end of the frame B in bearings formed by lugs F' and F², lugs F' being provided on the guide-bar 28 on the under surface thereof and lugs F² being attached to the side walls of the frame B and extending forward under the lugs F', as shown. The cover F of the magazine has rigidly attached thereto two upwardly-projecting ears 39^a, to each of which is rigidly united a laterally-projecting stud 40, and upon said studs 40 are pivotally mounted follower-fingers 38, each of which is normally thrown upward by means of a spring 37, one end of which is inserted into an opening in a lug carried by the follower-finger and the other end of which is inserted in an opening in the stud upon which the follower-finger is pivotally mounted. Each of the follower-fingers has associated therewith a pivoted "equalizer" 39, mounted upon one end of a pin 39^b, which extends through the ears 39^a upon the magazine-cover. Each of the pivoted equalizers is provided with an outwardly-projecting lug or stud 39^c, which engages with a curved slot provided therefor in the follower-finger with which the equalizer is associated, as best seen in Fig. 2. By means of the construction above described the upward movement of the free end of each of the follower-fingers is accompanied by a corresponding upward move-

ment of the equalizer associated therewith, and the simultaneous movement of the equalizer upward with its follower-finger serves to keep the cartridges in each chamber of the magazine in proper relation to the upper part 70 of the magazine and the cartridge-forks, by means of which the cartridges are shifted from the magazine into position under the barrel.

In order to insure proper alternate action 75 of the cartridge-forks 31 in shifting the cartridges from the two magazine-chambers, the automatic switch-cam 43 of peculiar design is pivotally mounted on the lower surface of barrel-strap 24 about midway between the ends 80 thereof, as shown. The forward end of the cam 43 is pivoted on a screw 43^a, and the rear end thereof is free to swing laterally and when shifted is held in either position by means of a small spring 44, one end of which is inserted 85 into an opening in barrel-strap 24 and the other end of which engages an opening in the upper surface of the switch-cam near its free end. The lateral movement of the switch-cam is limited by a stud 44^a, which engages 90 with a curved slot in the switch-cam and which is rigidly attached to the under surface of the barrel-strap 24. Switch-cam 43 is provided on either side, near its forward end, with an incline 43^b for engagement with the studs 33^b, 95 provided on the spring-fingers 33, which serve as locks for the cartridge-forks. Projecting downward from the lower surface of the switch-cam is a diamond-shaped portion 43^c, the sides of which are adapted to contact with ribs 31^c on the upper surface of the cartridge-forks 31 in a manner hereinafter to be explained.

When it is desired to use the gun, the fore end E should be grasped and moved forward to the full limit of its movement, carrying with it the connecting-rod 30 and the barrel D, it being assumed that the catch on pivoted member 36 is depressed, so as not to engage with the depending lug on the forward end 105 of guide-bar 28. As the fore end E starts forward it travels a short distance before imparting any movement to the barrel D. During this first portion of this movement the fore end causes the connecting-rod 30, which 110 is held in engagement therewith by means already explained, to travel forward, and by the engagement of the cam-grooves on the connecting-rod with the lugs upon the locking-bolt 34 the said locking-bolt is drawn down, so that the ribs upon the upper end thereof are disengaged from the corresponding ribs 115 provided on the breech-piece 23, thus releasing the barrel of the gun, so that it may be carried forward by the continued movement 120 of the fore end. Simultaneously with the retraction of the locking-bolt the eccentric-lever 18 is swung upon the pivot-screw 8^a by engagement with the stud provided for that 125 purpose upon connecting-rod 30 near its rear 130

end. As the curved arm of the eccentric-lever swings forward the lug on the upper end thereof engages with the hammer 8 and throws it backward into position for engagement by the sear 21, which is held normally in position to engage with the shoulder provided on the hammer 8 by means of the spring carried by the safety-set 10, which causes the arm 9° on the trigger to be normally thrown backward, and the stud 9^a on said arm engaging the slot provided therefor in the arm 21^c on the sear holds the sear normally in position for engagement with the shoulder on the hammer 8. The swing of the eccentric-lever 18 upon its pivot also brings it into engagement with the upper portion of the knock-off member 17 and swings the latter upon its pivot, so that the curved end thereof is thrown upward for the hook provided at the extremity thereof to engage with the lug provided for that purpose on the safety-set 10. The first portion of the forward movement of the connecting-rod 30 brings the cam 30° at the rear end thereof into engagement with the stud at the forward end of trigger-locking lever 20, which causes the forward end of said lever 20 to be depressed and the safety device 11 to be forced rearward, so that the end thereof enters the recess 9^c in the body portion of the trigger, so positively locking the trigger in position and preventing accidental release of the striker by a pull upon the trigger when the gun is open. When the safety device 11 moves into operative position engaging the trigger, as above specified, the lug at the forward end of the lock-latch 13 engages with the lug at the rear of safety device 11 and holds it firmly in operative position, from which it cannot be disengaged until the reverse of the connecting-rod 30 to its normal position.

When the fore end has traveled forward far enough to produce a movement of the locking-bolt 34 and in the gun-lock, as above described, the pawl 25 in guide-loop 29 engages with the slot provided for it in grooved barrel-strap 24 and the loop 29 contacts with the stop-screw 24^b and causes the barrel to travel forward with the fore end during the remainder of its movement, thus opening the breech of the gun to permit the introduction of a cartridge into the barrel and if the gun has been fired permitting the extraction and ejection of the empty shell. As the fore end approaches the forward limit of its movement the elevator-lever 27 is swung upon its pivot by the engagement of the stud at the forward end of the lever with the incline in the cam-groove on the connecting-rod 30 near the rear end thereof. This movement of the elevator-lever raises the elevator, as shown in Fig. 13. When the fore end has reached the limit of its movement and the breech of the gun is fully opened, the magazine-cover F is opened by pressure upon the latch 14 and the two maga-

zine-chambers are filled with cartridges introduced separately or in clips or partly separate and partly in a clip. The magazine-cover is then closed and latched and a cartridge introduced into the barrel of the gun before closing it. When the magazine has been charged and the cartridge introduced into the barrel of the gun, the sliding fore end is moved backward, bringing with it the barrel and the connecting-rod 30. As the connecting-rod 30 moves rearward the stud at the forward end of the elevator-lever 27 travels along the lower portion of the cam-groove in the connecting-rod, and about midway of the return movement of the connecting-rod said stud engages with the inclined forward end of said lower portion of the cam-groove and causes the cartridge-elevator to be lowered to its normal position. Further rearward movement of the connecting-rod brings the rear portion of the connecting-rod into engagement with the curved arm of the eccentric-lever 18 and causes it to return to its normal position, leaving the other parts of the lock mechanism in the position above specified. The locking-bolt 34 is of course thrown into engagement with the breech-piece by the action of the cam-grooves formed on the connecting-rod upon the cam-lugs provided on the locking-bolt for engagement therewith. As the fore end travels rearward the barrel reaches the limit of its rearward travel before the fore end contacts with the forward end of the frame B, and when this occurs the pawl 25 is released from engagement with the slot in the grooved barrel-strap 24 by the passage of the end of the pawl over the lug 28^a, provided therefor on the guide-bar 28. As the barrel moves rearward with the fore end the cartridge-fork upon the side toward which the switch-cam 43 is swung is thrown inward toward the median line of the gun by the engagement of the rib 31° on said cartridge-fork with the diamond-shaped downwardly-projecting portion of said cam. This movement of the cartridge-fork throws the cartridge from the magazine-chamber in which said fork works into position to be gripped by the spring-jaws of the elevator when the cartridge is forced backward by the continued rearward movement of the breech-piece, upon the under surface of which is provided a curved lug 23^a for engagement with the cartridge to effect this result. After the cartridge in the gun-barrel has been fired the fore end of the gun is moved forward, as explained, and all of the movements of the mechanism already described as brought about by the forward movement of the fore end again take place. In addition thereto the empty shell of the cartridge which has just been fired is withdrawn from the barrel by the extractor 3 and is thrown rearward and to the left by the forward impulse of the ejector 4 as soon as the gun-barrel is moved forward far enough for the end of the cartridge to clear it.

With the forward movement of the gun-barrel the lug 33^b upon the spring-finger 33 on the side of the gun toward which the automatic switch-cam 43 is swung engages with 5 the said cam to swing it to the opposite side of the gun. Immediately after the swinging of the switch-cam to the opposite side of the gun takes place the spring-finger 33, to which is attached the lug 33^b, which swings the switch- 10 cam, is forced downward by the depression of the lug 33^b as it passes under the switch-cam. The depression of the said spring-finger in the manner explained lowers the lug 33^c near the rear end of said spring-finger sufficiently to 15 permit the cartridge-fork, which had been held in position in the median line of the gun by said lug 33^c, to return to its normal position, so that on the return movement of the gun the spring at the rear end of the cartridge- 20 fork may pass outside of a cartridge in the magazine. The upward movement of the cartridge-elevator, which takes place at the end of the forward movement of the barrel at this time causes the cartridge which had 25 already been forced into the spring-jaws of the elevator by the closing movement of the gun-barrel previous to firing to be raised into alinement with the bore of the gun-barrel, so that when the gun is closed said cartridge will 30 enter the barrel and be held there when the elevator descends. Upon the return movement of the fore-end to close the gun the switch-cam 43, which, as above explained, has been swung to the opposite side of the gun, 35 engages with the other of the cartridge-forks and throws a second cartridge into position under the gun-barrel, where it is gripped by the elevator-jaws as the gun-barrel approaches the rearward limit of its movement.

40 In the foregoing description of the operation of the gun it has been assumed that it is desired to use it as a magazine-gun. When it is desired to cut off the magazine from the gun and use it as a single-shot firearm, the 45 rear end of the curved member 36 should be pressed upward. This will throw the catch at the rear end of said curved member into position to engage with the lug at the forward end of the guide-bar 28 and will prevent the 50 sliding loop 29 from moving far enough forward to cause the operation of the cartridge-elevator, thus preventing the passage of a cartridge from the magazine into alinement with the bore of the gun-barrel.

55 Owing to the simplicity of the mechanism by which the change from single-shot to magazine action or the reverse is accomplished the change may be made instantly without removing the gun from the shoulder.

60 It will be observed that in a rifle constructed as hereinbefore described the end of the barrel is completely covered at the time of firing by the frame, which is without any openings at the top through which gases can escape, and that at the time of firing the breech

end of the barrel is held positively in engagement with the frame by the wedge action of the locking-bolt. It will also be observed that the end of the barrel is brought directly against the frame and that an additional length 70 of the barrel is secured thereby, thus permitting the sights to be brought closer to the eye of the user than is common in magazine-fire-arms.

As the barrel, fore-end, and guide-loop 29 75 are connected with the stock and its associated mechanism only by engagement of the upper edges of the side walls of frame B with the grooves in barrel-strap 24 and by the engagement of the lug at the forward end of connecting-rod 30 with the spring 35, the barrel and fore-end may be very readily detached from the stock and its mechanism by pressing equally upon the two ends of curved member 36, causing the lug 36^a to ride over the elevated portion 35^b of the spring 35, thereby depressing said spring, as seen in Fig. 12, and permitting the disengagement of connecting-rod 30 from said spring, so that the gun-barrel and fore-end may be drawn forward out 80 of engagement with the stock. This construction enables the gun to be "taken down" instantly when desired, facilitates inspection and cleaning, and permits the gun to be carried in a case occupying small space when the 85 gun is not required for immediate use.

In the foregoing paragraphs the description has been confined to the constructive features found in the sporting pattern of the rifle. When a rifle for military service is constructed in accordance with this invention, certain modifications are made in the structure, as hereinafter described. These modifications are illustrated in Figs. 28 to 30, inclusive. The fore-end instead of being the form best 105 shown in Fig. 1 is of the form shown in Figs. 28 and 29, comprising an extension 45, inserted into a metal cap 46, rigidly secured to the rifle-barrel by means of a strap 47, and the movable member E, recessed at its forward 110 end to telescope over the cap. The guide-bar 28 is prolonged and extends through a suitably-shaped aperture in the end of the cap 45, as seen in both Figs. 28 and 29, thus forming a stronger and more solid support for the 115 guide-bar than is afforded in the sporting pattern of the rifle and adapting it for the heavier use to which a military rifle is subjected. Otherwise the structure of the fore-end and the mechanism contained therein is as herein- 120 before described.

The rifle for military service is constructed, preferably, with a straight stock instead of a stock with a pistol-grip, as illustrated in Fig. 1, and the trigger-set provided in the sport- 125 ing pattern of rifle is eliminated, thus doing away with the member 10 (best shown in Fig. 9) and making unnecessary a hook at the rear end of member 17. The spring 10^a, attached to the member 10, is, however, retained, but 130

instead of being inserted into a slot in member 10, as shown in Fig. 9, is attached by a small screw or rivet to the trigger 9, as shown in Fig. 30, in which is also shown the member 17 with the terminal hook removed therefrom. With these exceptions the lock mechanism is the same as that employed in the sporting pattern of rifle already described.

The cartridge-clip illustrated in Fig. 31 is one which is adapted for use in a rifle having a magazine of the type which I employ. It will be observed that the clip comprises a member 47^a, with overturned edges at one side and both ends to engage with the flanges at the heads of the cartridges inserted into the clip, and a member 48, having a turned-over edge along one side only. The member 48 is slidably associated with member 47^a, so that it may be moved longitudinally in either direction along the rear surface of the member 47^a until the end of member 48 coincides with the end of said member 47^a. By constructing the clip in this manner it is possible to use the same clip in either chamber of the magazine, it being understood that when used in the right chamber the sliding member 48 will be moved into coincidence with the member 47^a at one end, and when used in the left chamber the sliding member 48 will be moved into coincidence with the other end of member 47^a. When one end of member 48 coincides with one end of member 47^a, the other end of member 47^a will project beyond the end of member 48 a sufficient distance to allow a cartridge 35 to be withdrawn over the end of member 48.

Having thus described the construction and operation of my invention, what I claim as new, and desire to secure by Letters Patent, is—

40 1. In a magazine-firearm, the combination of a stock, guides extending forwardly from the stock, a barrel slidably mounted upon said guides, a guide-bar rigidly supported beneath said barrel and attached to the stock, a rib on said guide-bar near the forward end thereof, a metal strap secured to said barrel on the under surface thereof and having an opening, a guide-loop slideable on said strap and on said guide-bar, a spring-pressed pawl in said guide-loop adapted to engage the opening in said strap and to be forced out of engagement therewith by the rib upon said guide-bar, and a fore-end rigidly associated with said guide-loop.

55 2. In a magazine-firearm, the combination of a hammer, a trigger, a latch for said trigger, a sliding fore-end, and connections between said fore-end and said hammer and between said fore-end and said trigger-latch, whereby the forward movement of said fore-end cocks said hammer and locks said trigger.

3. In a magazine-firearm, the combination of a hammer, a trigger, a latch for said trigger, a lock to hold said trigger-latch positively 65 in operative position, and a sliding fore-end

operatively connected with the said latch and said hammer whereby the forward movement of the fore-end cocks the hammer, sets and latches the trigger and locks the trigger-latch positively in operative position.

4. In a magazine-firearm, the combination with a barrel, of a pair of cartridge-chambers one on either side of the barrel near the breech end, means in said chambers for raising the cartridges therein, and means for alternately 75 removing the uppermost cartridge in each chamber and introducing it into the barrel.

5. In a magazine-firearm, the combination with a barrel, of a pair of cartridge-chambers located one on each side of the barrel near the breech end thereof, a pivoted cartridge-shifter for each of said chambers, and means for operating said shifters alternately.

6. In a magazine-firearm, the combination of a barrel, a pair of cartridge-chambers located one on either side of said barrel near the breech end thereof, a pivotally-mounted fork lying in each of said chambers and forming means for shifting cartridges from said chamber into position beneath the barrel, means 85 for raising the cartridges in each of said chambers, and means for alternately actuating said forks to remove the uppermost cartridge in each of said chambers.

7. In a magazine-firearm, the combination 95 of a sliding barrel, a pair of cartridge-chambers located one on either side of the breech end of said barrel, a pivoted cartridge-shifting fork located in each of said chambers, means associated with said barrel for operating said forks alternately to shift the cartridge from the magazine-chamber into position beneath said barrel, and means for holding the fork in position under the barrel until the cartridge has been disengaged from 100 the fork.

8. In a magazine-firearm, the combination of a sliding barrel, a pair of cartridge-chambers located one on either side of said barrel near the breech end thereof, a pair of pivoted 110 cartridge-shifting forks, means associated with the barrel whereby the rearward movement of the barrel actuates one of said cartridge-forks and causes it to shift a cartridge into position beneath the barrel, and means for locking 115 said fork in position beneath the barrel until the forward movement of the barrel.

9. In a magazine-firearm, the combination of a stationary guide-bar, a barrel slidably mounted above said guide-bar, a pair of cartridge-chambers located adjacent to the breech end of said barrel one upon either side thereof and below the level of the barrel, a pair of pivoted cartridge-shifting forks adapted to shift the cartridges alternately from said 120 chambers into position under said barrel, a pair of spring-fingers attached to said guide-bar and provided with locking-lug adapted to lock said forks alternately in position under said barrel when they have been shifted 125 130

into position thereunder, and means associated with said barrel for disengaging said locking-lugs and said forks.

10. In a magazine-firearm, the combination of a sliding barrel, a pair of cartridge-chambers located one on either side of said barrel near the breech end, a stationary member beneath said barrel, a pair of cartridge-shifting forks pivotally mounted on said stationary member and adapted to shift cartridges from said chambers into position beneath said barrel, a pair of spring-fingers provided on said stationary member, each of said spring-fingers having a pair of upwardly-projecting lugs one of which is adapted to lock the cartridge-shifting fork in position under the barrel after a cartridge has been shifted into position beneath the barrel, and means provided beneath the barrel for engaging with the other lug upon each of said spring-fingers to depress either of the fingers and release the cartridge-fork locked by either of said fingers.
11. In a magazine-firearm, the combination of a sliding barrel, a pair of cartridge-chambers located one on either side of said barrel near the breech end, a stationary member beneath said barrel, a pair of forks pivotally mounted on said stationary member and adapted to shift cartridges from said chambers into position beneath said barrel, a pair of spring-fingers attached to said stationary member and each having a pair of upwardly-projecting lugs the rear one of which is adapted to lock the fork in position beneath the barrel, and a pivoted cam mounted beneath the barrel and adapted to contact with the forward lugs on said spring-fingers and to depress said spring-fingers sufficiently to release said cartridge-shifting forks.

12. In a magazine-firearm, the combination of a sliding barrel, a pivoted cam secured in position beneath said barrel, a stop-lug for limiting the pivotal movement of said cam, a spring adapted to hold said cam always in contact with the stop-lug, a pair of cartridge-chambers, a pair of cartridge-shifting forks located in said chambers, and ribs upon said forks adapted to be engaged by said cam to operate said forks.
13. In a magazine-firearm, the combination of a sliding barrel, a pivoted spring-actuated cam secured beneath said barrel and movable therewith, a stationary member beneath said barrel, a pair of cartridge-chambers located one on either side of said barrel near the breech end, a pair of cartridge-forks pivotally mounted on said stationary member and adapted to shift cartridges from said chambers into position beneath said barrel, a rib provided on the upper surface of each of said forks and adapted to be engaged by said cam to operate the fork to which the rib is attached, latch mechanism provided on said stationary member and adapted to engage said forks to hold either in position beneath the barrel after shift-

ing a cartridge, said latch mechanism being adapted to be engaged by said cam and thrown into operative position.

14. In a magazine-firearm, the combination of a sliding barrel, a magazine adjacent to the breech end of said barrel at one side thereof and below the level of the barrel, means for shifting a cartridge from the magazine to a position beneath the barrel, an elevator adapted to raise a cartridge from position beneath the barrel into alignment with the bore of the barrel, a rod having a cam-groove associated with the barrel and reciprocated thereby, a pivoted lever having one end connected with the elevator and the other end engaging the cam-groove in said rod, whereby the reciprocation of said rod raises and lowers said elevator.

15. In a magazine-firearm, a cartridge-elevator comprising a member mounted for vertical reciprocation, and a pair of spring-actuated cartridge-gripping jaws projecting forward from said member and each having the forward portion curved to conform to the contour of the cartridge and at the rear a vertically-disposed groove immediately in front of said member to permit the upward passage of the head of a cartridge.

16. In a magazine-firearm, a stationary member having laterally-projecting studs, a cartridge-elevator comprising a vertically-slidable plate having guide-loops engaged by said studs, and a pair of spring-actuated cartridge-clamping jaws projecting forward from said slidable plate.

17. In a magazine-firearm, the combination of a sliding barrel, a magazine adjacent to the breech end of said barrel, means for shifting a cartridge from said magazine to a position beneath said barrel, a downwardly-projecting lug at the breech end of said barrel, said lug being curved to correspond to the curvature of the cartridge and serving by engagement with said cartridge to hold the same in position beneath said barrel, and a cartridge-elevator beneath the breech of said barrel into which a cartridge will be forced by the rearward movement of said sliding barrel.

18. In a magazine-firearm having a barrel, a magazine below the level of said barrel, said magazine being open at the bottom for charging, a pivoted closure-plate for said magazine, a pair of lugs provided on said closure-plate, spring-actuated follower-fingers pivotally mounted on said lugs, said follower-fingers having slots intermediate of their ends, equalizer-fingers pivotally mounted on said closure-plate in the rear of said lugs, and studs provided on said equalizer-fingers and adapted to engage the slots in the follower-fingers, the cartridge-engaging end of such pivot members maintaining the same positions relatively to each other during the entire upward movement within the magazine.

19. In a magazine-firearm, the combination

with a slidable barrel, a breech-piece provided on its opposite sides and bottom with ribs and grooves, those on the sides being arranged on lines oblique to the axis of the bore, and a 5 slidably-mounted locking-bolt having similarly-disposed ribs and grooves for engagement with those of the breech-piece and exercising a cam-like action in forcing the breech-piece in the direction of breech-block of the 10 firearm.

20. In a magazine-firearm, a slidable barrel, a breech-piece rigidly secured thereto, a slid- 15 able locking-bolt disposed at right angles to said barrel for engaging with said breech-piece, cams provided on said locking-bolt, and a reciprocating member having grooves for engaging with said cams to throw said locking-bolt into and out of operative position.

21. In a magazine-firearm, a frame having 20 forwardly-extending portions forming guides, a barrel slidably mounted on said guides, a breech-piece rigidly secured to said barrel, a locking-bolt slidably mounted in said frame and engaging positively with said breech- 25 piece, a spring interposed between said locking-bolt and said frame to cause frictional engagement between said locking-bolt and said frame, and means for operating said locking-bolt.

30. 22. In a magazine-firearm, the combination of a pivoted hammer, an eccentric lever for cocking said hammer, a sear, a trigger, a trigger-latch, a lever for throwing said trigger-latch into operative position, and a reciprocating member engaging said eccentric lever and the lever for locking the trigger-latch and throwing them into operative position.

23. In a firearm, the combination of a hammer, a sear, a trigger having a recess formed 40 therein, a trigger-latch entering said recess, an automatic lock engaging said trigger-latch and serving to lock it in operative position, and a reciprocating member for cocking said hammer and throwing said trigger-latch into 45 operative position.

24. In a firearm, the combination of a hammer, a trigger having a recess, a trigger-latch entering said recess, an automatic lock engaging said trigger-latch and holding it securely in operative position, and a reciprocating 50 member operating on one movement to cock said hammer and throw said trigger-latch into operative position and serving upon the reverse movement to partially disengage the lock for said trigger-latch.

25. In a firearm, the combination of a sliding barrel, a locking-bolt for said barrel, a cartridge-elevator, a sliding fore-end, and a rod having cam-grooves adapted to be engaged by portions of said elevator and said locking-bolt and attached to said sliding fore-end. 60

26. In a magazine-firearm, the combination of a magazine, means for shifting cartridges from said magazine to said barrel, a sliding fore-end for imparting movement to said cartridge-shifting means, and a latch-pin upon said fore-end by means of which said cartridge-shifting means may be rendered operative or inoperative at will. 65

27. In a magazine-firearm, the combination 70 of a magazine, means for shifting cartridges from said magazine to the barrel, a lock, a sliding fore-end, connections between said fore-end and said shifting means and between said fore-end and said lock whereby the movement of said fore-end operates said cartridge-shifting means and said lock, and a catch upon said fore-end by means of which the movement of the fore-end may be limited so as to prevent the operation of the cartridge-shifting means without binding the operation of the lock. 80

In testimony that I claim the foregoing as my own I have hereto affixed my signature in the presence of two witnesses.

ALFRED MILROY NOLF.
